UNITED STATES PATENT OFFICE.

JAMES L. ANDERSON, OF ENGLEWOOD, NEW JERSEY, ASSIGNOR TO AIR REDUCTION COMPANY, INCORPORATED, OF NEW YORK, N. Y., A CORPORATION OF NEW YORK.

PROTECTION OF ACETYLENE LINES.

Application filed September 24, 1924. Serial No. 739,472.

In shops and factories where oxyacetylene welding and cutting torches are employed, using acetylene from generators, the permanent acetylene lines leading from the generator, and to which the torches are connected at various points by flexible hose, are more or less susceptible to rupture with danger of serious consequences.

In order to protect the generator from disturbances arising from faulty operation or misuse of the torches, a deep water-seal having a check valve is interposed in the line at a strategic point, so that back pressure and flame will be prevented from passing the point, the flame being extinguished by the water of the seal. The part of the line between the water-seal and the torches is nevertheless subject to an excess of internal pressure, which may be of either one of two orders. Usually, a backfire or flashback in the torch does not go beyond the mixing chamber of the torch, but at times, if the torch nozzle happens to be obstructed, it may be carried back into the acetylene line by a higher oxygen pressure. Then, if it continues to burn quietly at the point where the oxygen and acetylene meet, and is not extinguished at the water-seal, the pressure in the line rises at a certain rate and requires to be relieved. The combustion reaction may also develop into an explosive reaction, causing a large and instantaneous increase in pressure; or an explosive mixture introduced into the line in some manner from one of the torches and carried unburned, it may be to a point in the system far removed from its source, may subsequently become ignited by the attempt of some one to operate his torch. Such an explosion may tear apart the line, with escape of flame and gas, and it may also, in spite of barriers, drive back to the generator, where grave damage has been caused.

The apparatus herein described is designed to arrest and extinguish disturbances before they can reach the generator, and at the same time to vent the gas chamber of the water seal and the affected part of the line to the atmosphere. According to an important part of the invention the way to the atmosphere may be opened through one or both of two paths or branches, functionally in parallel relation, the particular functioning depending upon the nature and force of the disturbance. Both branches are nor-

mally closed, one branch being closed by an automatic, loaded, mechanical relief valve capable of functioning repeatedly without attention. The other branch, however, which it is advantageous to place in the direct line of action, is semi-permanently closed by a disk adapted to burst at excessive pressure. 60

A further feature of the invention relates to means enabling the water-seal to be charged with water without the entrance of air. 65

In the accompanying drawings forming part hereof:

Fig. 1 is an elevation, partly in vertical section, and with the intermediate part of the vent pipe broken out, of a water-seal and superstructure embodying the invention, adjacent portions of the gas line being shown; 70

Fig. 2 is a view on a larger scale, partly in section and partly in elevation, of the superstructure and the upper part of the water-seal chamber; and

Fig. 3 is a cross-section on the line 3—3 of Fig. 1. 80

The enclosure of the water-seal illustrated in these views is formed by a tight vertical tank 2 of strong construction, having a removable bolted cover 3 sealed by a gasket 4. 85

The inlet part of the acetylene line, coming from the generator, is marked 5, this part of the line, by suitable fittings, being connected to and passing downward through an opening in the cover and having the extension 6 which descends to near the bottom of the water chamber formed by the lower half of the tank more or less, and terminates in an upturned exit 7. This exit, disposed well below the water-level, is guarded by an automatic check-valve 8 arranged to open to pressure from the generator side 5, but to close against back pressure gas seeking entrance through the exit 7. 90

The water level of the seal, marked *a*, is established by a filling entrance and pipe in conjunction with an overflow pipe and exit. The filling and overflow openings are in the side of the tank approximately midway of the height, and are closed by removable plugs 9 and 10 respectively. Both the filling and the overflow pipes 11 and 12 connected with these openings extend far down within the tank, so that their lower ends are much below the water-level, and as indicated 105

110

at least as low as the gas exit 7. In this way the water body can be replenished from time to time without possibility of air getting in to form a combustible or explosive mixture with the acetylene.

In another opening in the cover 3, and communicating with the gas outlet chamber formed by the upper part of the tank, is a fitting 13, from which extends the service 10 side 14 of the acetylene line.

The fitting 13 is also the support and entrance limb for a superstructure, marked generally 15, which divides into two "parallel" branches 16 and 17, joined above to a 15 vent pipe 18 extending upward to discharge above the roof of the building. The roof line is represented by the horizontal line at the top of Fig. 1.

The branch 17 disposed in straight line 20 with the entrance limb 13 from the gas outlet chamber of the water-seal and preferably also in direct line with the chimney 18, contains a frangible disk 19 bolted between flanges 20. A spider 21 in the enlarged 25 chamber 22 above this disk is designed to keep pieces of the disk, when ruptured, from clogging of the outlet pipe 14.

The other branch 16 is shown carried off laterally from the entrance limb from a 30 second tee fitting 23, below the frangible disk, and turned upward by an elbow, to rejoin the first branch by a lateral nipple and another tee fitting 24 above the disk at the base of the vent pipe. Naturally, the 35 specific construction may be varied.

The branch 16 contains at a suitable point, preferably at its upper corner, a valve-chamber 25 containing an annular valve-seat 26 and a normally seated valve member 27 40 adapted to move bodily away from its seat in response to a definite pressure in the water-seal and line 14. This valve, which is illustrated as of a known type, is loaded by an adjustable spring 28, which, under all 45 normal conditions, holds the valve closed, but permits it to yield when the predetermined pressure exists.

Thus, if the system carries an acetylene gas pressure of 15 lbs. to the square inch, 50 which is customary, the relief valve will be loaded to open at a pressure somewhat above this value, for example at a pressure of 18 lbs. This will vent the seal and line under the less emergent abnormal conditions which 55 may occur from time to time, and which need not call for a shut-down or for repairs. In event of a true explosion, or in case of the valve 27 not functioning for any reason, the disk 19 will give away, and save 60 the system. It is best that this disk be calculated to withstand a comparatively high pressure, but to yield certainly and completely at a pressure such as to protect the permanent system from rupture or injury. 65 This pressure may be in the neighborhood

of 50 lbs. per square inch, but it will be understood that figures are given by way of illustration. In case of an explosion the instantaneous force of the reaction is delivered directly against the disk, shattering 70 it, and at the same time the valve 27 is forced open, so that two avenues of escape are afforded.

Excess gas back pressure or blow, whether due to a flashback combustion or an explosion, will be kept from the generator by the check-valve 8, and even should this valve fail, the direct and double vent from the seal to the atmosphere insures the generator against injury from this cause. Actual flame will be extinguished by the water body of the seal, at the time that one or both vent passages open so as to prevent any possibility of the flame being blown back to the generator, as for instance should there be a leaky or insufficiently charged seal.

What I claim:

1. A safety apparatus for acetylene gas lines comprising in combination with the line, a water-seal having a gas inlet and an outlet chamber, and a superstructure in free communication with the outlet chamber of the water-seal, said superstructure comprising two normally-closed branches in parallel 95 by one or both of which excess pressure may open an escape to atmosphere, one of said branches containing a loaded mechanical relief valve adapted to open at a pressure somewhat above the normal of the line connected with said outlet chamber, and the other branch being closed by a frangible disk calculated to yield to excessive pressure.

2. A safety apparatus for acetylene gas 105 lines comprising in combination with the line, a water-seal having a gas inlet and an outlet chamber, a cover for the chamber, and a superstructure having a limb opening through said cover, a service line conduit 110 connected with said limb, a vent pipe, and two normally-closed relief branches interposed between said limb and line conduit on the one hand and the vent pipe on the other hand, one of said branches containing a 115 loaded mechanical relief valve and the other branch being closed by a frangible disk.

3. A safety apparatus for acetylene gas lines comprising in combination with the line, a water-seal having a gas inlet and an 120 outlet chamber, and a superstructure in free communication with the outlet chamber of the water-seal, said superstructure comprising two normally-closed branches in parallel 125 by one or both of which excess pressure may open an escape to atmosphere, one of said branches containing a loaded mechanical relief valve and the other branch being closed by a frangible disk, the branch containing said disk being in straight line communica- 130

tion with the outlet chamber of the water-seal.

4. A safety apparatus for acetylene gas lines comprising in combination with the line, a water-seal having a gas inlet and an outlet chamber, and a superstructure in free communication with the outlet chamber of the water-seal, said superstructure comprising two normally-closed branches in parallel by one or both of which excess pressure may open an escape to atmosphere, one of said

branches containing a loaded mechanical relief valve and the other branch being closed by a frangible disk, the branch containing said disk being in straight line communication with the outlet chamber of the water-seal, while the branch containing the relief valve is carried off laterally from the straight branch and then extended upwardly to a junction therewith above the disk, and a vent pipe extending from the junction.

JAMES L. ANDERSON.
